(No Model.)

A. PETTERSON,
ADJUSTABLE STOVEPIPE SUPPORT.

No. 476,815.

Patented June 14, 1892.

UNITED STATES PATENT OFFICE.

ALBERT PETTERSON, OF ST. PAUL, MINNESOTA.

ADJUSTABLE STOVEPIPE-SUPPORT.

SPECIFICATION forming part of Letters Patent No. 476,815, dated June 14, 1892.

Application filed February 2, 1891. Serial No. 379,899. (No model.)

To all whom it may concern:

Be it known that I, ALBERT PETTERSON, of St. Paul, Ramsey county, Minnesota, have invented certain Improvements in Adjustable 5 Stovepipe-Supports, of which the following is a specification.

My invention relates to improvements in attachments to stovepipes for connecting them to the ceiling or other support, its object being to provide a device which is readily attached to or detached from the pipe and the wall or ceiling, and may be adjusted to any desired length, so as to bring the pipe into the desired position.

15 To this end my invention consists in a two-part clasp to surround the pipe and an extensible arm to connect said clasp with a supporting-hook, the length of the arm being adjusted as desired.

20 My invention further consists in the construction and combination hereinafter described, and particularly pointed out in the claims.

In the accompanying drawings, forming 25 part of this specification, Figure 1 is a front elevation of my improved support. Fig. 2 is a side elevation of the same. Figs. 3 and 4 are partial details of the arm and extension-piece, and Figs. 5 and 6 are enlarged details 30 of the spring-catch for locking together the arm and extension-piece.

In the drawings, 2 represents a substantially semicircular band or strap of sheet metal provided at one end with an eye or opening 4 and at its other end with a hook 6, this strap forming one member of the pipe-clasp. The other member 8 is of substantially the same form, having, also, an eye 4 and hook 6, by means of which the two parts are readily 35 connected together, thus forming a circular band for inclosing the pipe. The member 2 of the clasp is slipped through a loop 12, turned at right angles to the body of the arm 14, also preferably made of sheet metal, so 40 that the arm extends at right angles to the tangent of the strap 2 at the point of its connection with the arm. At the outer end of the arm is provided an opening 16 in the form of a four-pointed star, or a cross formed by 45 50 the intersection of a longitudinal and a transverse slot. Arranged in this opening is a wire spring-catch 18, bent upon itself with its ends

20 outturned and slipped through the opening 16, the spring of the body tending to spread the ends, and thus to hold them at the 5 extremities of either slot of the opening, so that the catch will be held with its plane either at right angles or in line with the arm. Sliding upon this arm is a longitudinally-slotted extension-strip 22, having at its lower end 6 a clasp 24, partially embracing the arm, and having its outer end bent upon itself to form a transverse eye 26, adapted to be slipped upon a right-angled hook 28, secured to the ceiling or wall. The longitudinal slot 30 of 6 the extension-piece is provided at intervals with oppositely-arranged notches 32, corresponding approximately to the size of the transverse slot of the opening in the end of the arm to receive the spring. This extension-piece being slipped upon the arm, the spring-catch is inserted into the opening 16 and turned to stand in line with the arm, when it can be slipped through the slot in the extension-piece, and then, being given a 7 quarter-turn, will spring outwardly into the notches of the slot and hold the extension-piece fixed upon the arm. The position of the parts is adjusted by simply giving the spring-catch a reverse quarter-turn and sliding the 75 parts upon each other to the desired position, when the catch is again turned to lock them together. This attachment may be used as a support for suspending a horizontal pipe or as a lateral brace for a vertical pipe. 8

The device, as described, may be attached to different sizes of pipes by simply using a detachable clasp member of such size as to inclose the pipe, the members bending to adapt themselves to the surface of the pipe. 80

I claim—

1. In a device of the class described, the combination of a two-part clasp to surround the pipe, a sheet-metal arm rigidly connected to one member of the clasp, a sheet-metal extension-piece sliding upon said arm and adapted to be attached to a hook or other support having a longitudinal slot and oppositely-arranged notches in the sides of the slot, and a spring-catch adapted to be inserted 95 through said slot and turned transversely thereof to engage said notches and to lock the extension-piece upon said arm, substantially as and for the purposes set forth. 100

2. The combination of the semicircular sheet-metal clasp, members 2 and 8, adapted to surround the pipe and to be connected end to end, an arm having a loop firmly engaging the member 2 and having an opening formed by intersecting longitudinal and transverse slots therein, a spring-catch arranged in said opening, and the extension-piece 22, sliding upon said arm and adapted to be connected to a suitable support and having the longitudinal slot 30 and the notches 32 in the sides of said slot, adapted to receive said spring-catch, substantially as and for the purposes set forth.
3. In a device of the class described, the combination, with the pipe-clasp, of a two-part attachment to said clasp, comprising a sheet-metal arm connected to the clasp and a sheet-metal extension-piece sliding upon said arm and connected to the support, one of said

members having an opening therethrough 20 formed by the intersection of a transverse and longitudinal slot and the other member having a longitudinal slot and oppositely-arranged notches in the sides of said slot corresponding in size to the transverse slot of the 25 opening in the other member, and a laterally-expanding spring-catch held in said opening in one member and extending through the slot in the other member and adapted to engage the notches of its slot, substantially as 30 described.

Witness my hand this 24th day of January, 1891.

ALBERT PETTERSON.

In presence of—

T. D. MERWIN,
C. L. CALDWELL.
